ARTHUR GAUDENZI, OF BADEN, SWITZERLAND, ASSIGNOR TO AKTIENGESELLSCHAFT BROWN BOVERI & CIE., OF BADEN, SWITZERLAND, A JOINT-STOCK COMPANY OF SWITZERLAND

VAPOR RECTIFIER

Application filed February 13, 1928, Serial No. 253,943, and in Germany May 13, 1927.

This invention relates to electric power rectifiers of the mercury vapor type, and finds particular utility in its application to metal tank polyphase rectifiers such as described in the Bulletin of the Brown Boveri Company of Baden, Switzerland, entitled Brown-Boveri mercury arc rectifiers for large outputs published July, 1926.

The general object of the invention is the provision of an improved construction and an improved method for operating rectifiers of this type, which construction and method are adapted to prevent backfiring or reversals of the current flow in the rectifier or in the several anodes thereof.

Other objects are the provision of such a construction and method of operation which are simple and reliable.

Still other objects will be pointed out or indicated hereinafter or will become apparent to one skilled in the art upon employment of the invention in practice.

In the drawing forming a part of this specification I illustrate diagrammatically various structural arrangements in which the invention may be embodied or by use of which it may be practiced, but it is to be understood that these are presented for the purpose of illustration only and that they are not to be accorded any interpretation having the effect of limiting the claims short of the true and most comprehensive scope of the invention in the art.

In said drawing

35 Fig. 1 is a schematic illustration in the nature of a sectional elevation of a rectifier, illustrating the essential features of one arrangement of apparatus embodying the invention, but omitting various parts of the rectifier itself.

Fig. 2 is a similar illustration but showing a different arrangement of the features of the present invention.

Fig. 3 is a similar illustration representing two other forms of apparatus comprehended by the present invention.

Fig. 4 is a cross-section detail on line 4—4 of Fig. 3.

In the operation of mercury-vapor rectifiers, there is alternately applied to each

anode a positive and a negative voltage, the anodes permitting current to flow to the cathode when the respective anode is positive, but acting as check valves, and preventing current flow to the cathodes when the respective anode is negative. The maintenance of this valve action of the anodes, on which the operation of the rectifier is based, presents one of the greatest difficulties in the development of satisfactory and practical power rectifiers. Very often an anode loses the check valve action at the moment when it is negative, resulting in a current reversal or backfire, that is, a short-circuit current flow from the active positive anodes to the temporarily inactive negative anode.

I have conducted extensive experimentation for the purpose of determining the factors or conditions which contribute to reverse arcing, and have ascertained that reverse arcing is more likely to occur if there is a concentration of mercury vapor or gas in the neighborhood of the anodes. The arc at the mercury surface produces strong evaporation of mercury, and as a result, there is a tremendous blast of mercury vapor continuously passing from the cathode to the cooled walls of the tank. This blast must be kept away from the anodes. But it is not sufficient simply to divert the rising stream of mercury vapor away from the anodes, as the expansion of the mercury vapor fills the entire casing with it and tends to produce an excessive density of the gas and vapor about the anodes.

The present invention provides, in addition to the diverting of the mercury vapor from the anodes, for the reduction of the vapor density in the region of the anodes by maintaining there a temperature properly in excess of what would be the normal temperature of the vapor in those localities. The heating may be confined principally to the spaces enclosed by the anode shields, and may be effected by suitable heat-generating or heat-maintaining elements which are supplied either by the rectifier current or from a separate source.

Examples of such heating arrangements for the anode space are illustrated in the drawing, wherein the reference numeral 10

designates a rectifier casing of metal, 11 the cathode of mercury insulated from the vessel, and 12 and 12' respective anodes insulatedly mounted on the top of the vessel and supplied from a suitable transformer through the anode leads 12^a. The anodes are housed in relatively long tubular shields 14 which are open at the bottom. These shields are ordinarily made of metal and the anodes with the shields are so arranged away from the center of the rectifier that the vapor blast is diverted from the anodes and mercury particles prevented from impingement upon the anodes, in the well known manner as found for instance, in the present Brown Boveri rectifiers described in the Bulletin of 1926, referred to before. In order to reduce the possibility of backfire, special heating means are provided in the rectifier for decreasing the density of the vapor in the region adjacent to the anodes. In the example shown in Fig. 1 heating elements 15, in the form of coils of resistance wire, are disposed within the shields, being insulated from them, if they are metal, and also from the anodes and other portions of the rectifier. These heating elements may be supplied from a transformer 16 by way of connections 17, the energization of the heating elements being controlled by a switch 18, and the heating elements associated with different anodes being shown connected by lead 19. Effective results are obtained by maintaining the heating elements at a temperature of 500° to 800° centigrade. It is advantageous if heating of the anode spaces is effected before the operating current is impressed on the rectifier itself, and to permit this the transformer 16 may be a special transformer, which may be disconnected if sufficient heating effect can be supplied to the heating elements by the rectifier arc itself.

The example illustrated in Fig. 2 differs from that shown in Fig. 1 in having the heating coils 15' disposed outside the anode shields 14, but separated from the rest of the vacuum space by additional shields 20. The anode space is thus heated indirectly through the medium of the intervening shield, which shield may be equipped with various other heating elements arranged to derive their heat from the arc and maintain the heat in the enclosed space.

The other figures illustrate various arrangements of heating elements which derive their heat from the arc. A general requirement of such heating elements is that they be of such material and so arranged as to be heated by the arc to such a degree that they are enabled to maintain the anode space at the desired temperature during the period in which the anode is carrying no current. In general, this energy can be obtained from the arc only at the price of a considerable voltage drop, but by suitably designing such heating elements, excessive voltage drops may be

avoided. When these elements are made of metal and are heated by the rectifier current only, they should be capable of being brought to a dull red heat in a very short time, but must not fuse under the highest overloads. Consequently, they should preferably be constructed of some heat-resisting, non-friable metal such as tungsten, tantalum, molybdenum or iridium; however, iron or chrome nickel, which are not attacked by mercury, may also be used.

Such arrangement is shown in connection with anode 12 in the rectifier illustrated in Fig. 3, and in the horizontal section of the anode 12 in Fig. 4. It comprises a plurality of parallel vertically disposed metal rods 21 supported on the shield 14 by slender spiders 22 extending from a central thicker rod 23. These rods are heated by the discharge current passing between the anode and the cathode and are constructed so as to be maintained at a dull red heat, and be able to heat the gas and vapor in the space within the shield 14.

In the arrangement associated with the anode 12' in Fig. 3, the anode shield 14' of metal is especially equipped to function as a heating element by having its outer surface highly polished and its inner surface roughened or formed with projections in the nature of heating elements, as designated at 14^a. While it is of importance to have the anode shields well heat insulated from the casing in all instances, it is of particular importance with this form of heating device. This form anode shield heater is of special advantage, because it avoids increase in the voltage drop across the forward or rectified current arc to a greater extent than the other forms.

As seen in the drawing, the shields surrounding the anodes are made in the form of relatively long tubular members. The anodes with the shields are disposed on the sides of the rectifier tank, the shields having openings at the bottom at a distance below the anodes. The shield openings lie outside the space above the cathode area so as to prevent the mercury blast from the cathode from entering into the shields. The heating elements for superheating the anode region are disposed adjacent to the anode surfaces and are so positioned as to interfere as little as possible with the play of the arc through the anode shield openings. In all of the arrangements, the heating members within the interior of the anode shields occupy only a small part of the total cross-sectional area of the tubular space within the shield so that the arc is free to play through the relatively large area tubular spaces formed between the heating members. The mouth of the shield is in all cases left free, the heating members terminating at a distance back of the shield opening. In all of the arrangements the cross-sectional area within the shields occupied by the heating members is less than one-half of the open-

ing at the mouth of the shield through which the arc passes.

It will be understood that in the foregoing illustrations and descriptions, reference has been omitted to many of the well-known features of the rectifier itself, the disclosures herein being principally concerned with the novel heating arrangement and novel method of operation of the rectifier which involves the heating or maintenance of the temperature of the spaces about the anodes during their periods of inactivity, as well as during their active periods, for the purpose of effecting a reduction of the vapor density and gas density in those regions. This is effective to reduce the possibility of reverse arcing to an inactive anode.

What I claim is:

1. In a vapor rectifier comprising a hermetically closed evacuated vessel, a cathode and a plurality of anodes insulatingly mounted within said vessel and adapted to develop vapor during operation, tubular shields surrounding said anodes arranged to divert the stream of vapor from said anodes, each of said shields having an opening for passing the arc therethrough, and electrical heater elements within said shields in front of said anodes at a point back of said opening proportioned to be heated during operation by electric current to a temperature of the order of 500 degrees centigrade or more for reducing the gas density in the space adjacent to said anodes.

2. In a vapor rectifier comprising a hermetically closed evacuated vessel, a vaporizable cathode and a plurality of anodes insulatingly mounted within said vessel, tubular shields surrounding said anodes arranged to divert the stream of vapor from said anodes, each of said shields having an opening for passing the arc therethrough, and electrical heater elements exposed within said shields in front of said anodes at a point back of said opening and proportioned to be heated during operation by electric current to a temperature of the order of 500 degrees centigrade or more for reducing the gas density in the space adjacent to said anodes, said heater elements occupying a relatively small part of the cross-sectional area of the tubular space within said shields.

3. In a mercury-vapor rectifier, a hermetically closed evacuated vessel, an insulated cathode at the bottom of said vessel, a plurality of anodes at the top of said vessel, said anodes acting alternately as valves preventing current flow while the potential applied to said anodes is negative, and permitting current flow in the intermediate periods when they are at positive potential, tubular metallic shields individually enclosing said anodes, said shields having openings at the lower ends thereof at a distance from said anodes so arranged as to cause the vapor from said

cathode to be diverted from said anodes, and electrical heater elements disposed inside said shields in front of the anodes and proportioned to be heated during operation by electric current to a temperature of the order of 500 degrees centigrade or more, said heating means being so arranged as to leave unobstructed at least one-half of the total cross-sectional area of the tubular space within said shields.

4. In a mercury-vapor rectifier, a hermetically closed evacuated vessel, an insulated cathode at the bottom of said vessel, a plurality of anodes at the top of said vessel, said anodes acting alternately as valves preventing current flow while the potential applied to said anodes is negative, and permitting current flow in the intermediate periods when they are at positive potential, tubular metallic shields individually enclosing said anodes, said shields having openings at the lower ends thereof at a distance from said anodes so arranged as to cause the vapor from said cathode to be diverted from said anodes, and electrical heater elements disposed inside said shields between the anodes and shield openings, and proportioned to be heated during operation by electric current to a temperature of the order of 500 degrees centigrade or more, said heater elements leaving entirely unobstructed the openings of said anode shields and leaving unobstructed at least one-half of the total cross-sectional area of the tubular space within said shields.

5. In a mercury-vapor rectifier, a hermetically closed evacuated vessel, an insulated cathode at the bottom of said vessel, a plurality of anodes at the top of said vessel, said anodes acting alternately as valves preventing current flow while the potential applied to said anodes is negative, and permitting current flow in the intermediate periods when they are at positive potential, tubular metallic shields individually enclosing said anodes, said shields having openings at the lower ends thereof at a distance from said anodes so arranged as to cause the vapor from said cathode to be diverted from said anodes, and electrical heater elements within said anode shields in front of said anodes and proportioned to be heated during operation by electric current to a temperature of the order of 500 degrees centigrade or more, said heating means extending for a substantial length in the direction of the shields and terminating at a distance back of said anode openings leaving substantially unobstructed the entire cross sectional area of said openings.

6. A vapor discharge device comprising a gas tight vessel containing vapor, a cathode, an anode for maintaining a discharge with said cathode through said vapor, a tubular sleeve surrounding said anode and confining a portion of the discharge path in front of said anode, and electrical heater elements ex-

posed to the space within said shield in front of said anode and proportioned to be heated during operation by electric current to a temperature of the order of 500 degrees centigrade or more.

- 5 7. A vapor discharge device comprising a gas tight vessel containing vapor, a cathode, an anode for maintaining a discharge with said cathode through said vapor, a tubular
10 sleeve surrounding said anode and confining a portion of the discharge path in front of said anode, and electrical heater elements supported by said sleeve in front of said anode for reducing the vapor density in said space,
15 said heater elements leaving substantially unobstructed the tubular discharge path through said sleeve and proportioned to be heated by electric current during operation to a temperature of the order of 500 degrees centigrade or more.
- 20 8. A vapor-discharge device comprising a gas tight vessel containing vapor, a cathode, an anode for maintaining a discharge with said cathode through said vapor, a shield surrounding said anode and confining a portion of the discharge path in front of said anode, and electrical heater elements associated with said shield in front of said anode and proportioned to be heated during operation by electric current to a temperature of the order of 500 degrees centigrade or above for reducing the vapor density within said shield.
- 25 9. A vapor-discharge device comprising a gas tight vessel containing vapor, a cathode, a plurality of anodes for maintaining a discharge with said cathode through said vapor, a plurality of shields surrounding said anodes and confining a portion of the discharge path in front of said anodes, and electrical heater elements exposed to the spaces within said shields in front of said anodes and proportioned to be heated during operation by electric current to a temperature of the order of 500 degrees centigrade or above for reducing the vapor density within said shields.
- 30 45 In testimony whereof I have hereunto subscribed my name this 13 day of January, A. D. 1928, at Zurich, Switzerland.
